UNITED STATES PATENT OFFICE.

THOMAS A. PUDAN, OF SACRAMENTO, CALIFORNIA.

PLATE OR DISH WASHER.

SPECIFICATION forming part of Letters Patent No. 414,446, dated November 5, 1889.

Application filed September 8, 1888. Serial No. 284,857. (No model.)

To all whom it may concern:

Be it known that I, THOMAS A. PUDAN, of the city and county of Sacramento, and State of California, have invented a new and Improved Plate or Dish Washer, of which the following is a full, clear, and exact description.

The object of my invention is to provide a simple and effective dish-washing machine; and it consists in the parts which will be hereinafter described, and pointed out in the claims.

Reference is to be had to the accompanying drawings, forming a part of this specification, in which similar letters of reference indicate corresponding parts in all the figures.

Figure 1 is a side elevation, partly in section and a part of the casing broken away. Fig. 2 is a section on the line $\alpha\alpha$ of Fig. 1, and Fig. 3 is a detail plan view of a portion of the box or casing and the operating mechanism. Fig. 4 is a detail of the rod I, the socket or casing H², and the gear J separated.

The box or casing consists of a bottom A, sides A' A², and ends A³ A⁴. The box is mounted on legs R. A division-wall B separates the box into two compartments C D. A grooved block b is fixed to the floor or bottom A adjoining the wall B. The inner sides of the end pieces A³ A⁴, within the compartment C, are provided with guard-cleats a. These cleats lie close to and parallel with the wall B, so as to form two guides, one on each side of the box, for the reception of the removable dish-holder E. A foot-block F, having grooves e on its upper side, is fixed to the lower side of the holder E. Said holder is provided with an opening E'.

G represents a dish.

A brush H is fixed to a back H', and said back is provided with a centrally-apertured casting H², having a diametrical slot across its outer end.

I is a rod provided on its outer end with a head I', and having a groove extending from a point midway of its length to near its inner end, which end is provided with a diametrical key H³, which, when the end of the rod is entered into the casting H², as shown in Figs. 2 and 4, engages the groove in the end of said casting. This rod is also provided with a bevel-

gear J, having an integral sleeve J', provided with an internal spline, which rests within the groove of the rod I. A spiral spring J² is interposed between the inner end of the gear-sleeve J' and the casting H², a washer H¹ being interposed between the casting and spring. The casing A' is provided with an opening in which is seated a flanged ring K. The gear-sleeve J' is mounted in said ring. 60

L is a bracket-arm provided with an opening for the reception of the rod I, and said rod is provided with a sleeve M, interposed between the bracket-arm and gear J.

N is a bracket fixed to the outer side of the casing A'. Each bracket L N is provided with an opening in which is mounted a rotary shaft O. A bevel-gear P is fixed to the inner end of the shaft O, and said gear meshes with the gear J. The outer end of the shaft O is 70 provided with a crank Q.

The water in the two compartments is indicated by the letter W.

The operation is as follows: The rod I has a longitudinal and rotary movement in its 75 bearings. In its longitudinal action said rod and its spline move freely through the gear J and its sleeve J'. The rotary movement of the gear J causes the rod and brush to rotate, the gear and rod being united by means of 80 the spline during a rotary action. By drawing the rod outward the spiral spring is compressed, and the brush can be easily removed and the plate-holder seated in the compartment C, as shown in the drawings. Then by 85 releasing the rod I the spring will force the brush inward against the plate-holder. Then by turning the crank Q the bevel-gears, rod I, and brush are rotated, and a plate placed in the holder in contact with the brush is cleaned 90 by the rotary movement of the brush and the water. Long dishes are washed by inserting first one end and then the other. The compartment D is for rinsing the dishes.

If very large plates or dishes are to be 95 washed, the frame E will first be removed in order that the lower edges of said plates or dishes may rest in the notches of the block b. The notches are inclined toward the partition B, so that when a plate is placed as in Fig. 2 100 its lower edge will be firmly held between both walls of the notch in which it rests.

Having thus described my invention, what I claim as new, and desire to secure by Letters Patent, is—

1. The combination, with the casing and the 5 horizontal shaft having a brush connected to its inner end, of a longitudinally-extending block in the bottom of the casing in front of and below the brush and having rearwardly-inclined notches in its upper face, substantially as set forth.

2. The combination, with the casing having 15 a vertical removable plate-supporting frame in one end provided with a horizontal notched block on its lower end, of the horizontal shaft having a vertical brush on its inner end facing the said supporting-frame, substantially as set forth.

3. In a washing-machine, the combination, with the box or casing, of a brush having a transversely-notched socket or casting H^2 on 20 its back, a shaft I, having a cross-bar on its inner end entering the said transverse notch to detachably connect it with the brush and extending at its opposite end out through the box or casing, a driving-gear journaled in the 25 end of the box or casing and through which said shaft passes, a spline-and-groove connection between said shaft and gear, and a spring on the shaft within the casing and pressing it forward, substantially as set forth.

THOMAS A. PUDAN.
